PRECISION FEED FOR MACHINE TOOLS
 Ralph E. Price and Charles E. Tolbert, Waynesboro, Pa.,
 assignors to Landis Tool Company, Waynesboro, Pa.
 Filed Feb. 21, 1963, Ser. No. 260,248
 14 Claims. (Cl. 51—165)

This invention relates to feed mechanisms for a machine tool, especially grinding machines, and more particularly, to means for effecting relatively small movements of a grinding wheel support at the end of a grinding operation.

In present day grinding, a workpiece is ground within limits of tolerances which are expressed in millionths of an inch. With present day feed mechanisms and grinding wheel support mountings, it is difficult to accurately move a wheel support even .0001".

When a driving force is applied to a grinding wheel support, it must be great enough to overcome starting friction and inertia. Once these forces have been overcome, a much lesser force is sufficient to keep the support moving. It is not possible to change from the starting force to the running force without moving the support too fast and too far. What happens is that a strain is built up in the feed mechanism until it is equal to or greater than the required starting force. When the starting resistance has been overcome, the starting force continues until the strain is released with the result that a support is advanced abruptly with the risk of damage to the workpiece. Furthermore, after the feed mechanism stops, the strain is relieved and causes the wheel support to continue to move or 'drift.' This movement may be prevented by means of a pressure operated device by which the relief of strain may be controlled.

It is, therefore, an object of the present invention to provide means to control the release of strain in the feed mechanism of a grinding machine.

Another object is to provide an adjustable resistance to the release of strain in a feed mechanism.

Another object is to provide means whereby a more or less conventional feed mechanism can be made to adjust a grinding wheel support by increments of .0001" or less.

Another object is to provide means for adjusting a wheel support feed mechanism while said wheel support is held against movement by a fluid pressure device, and bleeding said fluid pressure device to permit movement of said wheel support in response to adjustment of the feed mechanism until the desired adjustment is shown on an indicator in the path of said wheel support.

FIG. 1 is a front elevation of a centerless grinding machine.

FIG. 2 is a left hand end elevation, partly in section, taken on line 2—2 of FIG. 3, showing details of the wheel feed mechanism.

FIG. 3 is a partial front elevation, partly in section, taken on line 3—3 of FIG. 5, showing the feed mechanism.

FIG. 4 is a diagrammatic sketch of a wheel feed mechanism with hydraulic control elements for effecting relatively small increments of movement of a wheel support.

FIG. 5 is a partial right hand end elevation, partly in section, taken on line 5—5 of FIG. 3, showing the connections between the feed screw and ratchet mechanism.

FIG. 6 is a right hand end elevation of the feed mechanism.

For illustrative purposes, the invention is shown as applied to a wheel support of a centerless grinder to which the feed mechanism is applied. In some centerless grinders, the feed is applied to the grinding wheel support, and others, to the control wheel support. The

2

invention may also be applied to feed mechanisms of center-type machines.

Grinding wheel support 11 is slidably mounted on bed 10 of a centerless grinder. Grinding wheel 12 is rotatably mounted on wheel support 11. Control wheel 15 is rotatably mounted on control wheel support 16. Workpiece W is supported between wheels 12 and 15 on work rest blade 20 mounted on base 21 on bed 10.

The means for feeding wheel support 11 toward and away from workpiece W consists of a feed screw 30 rotatably and slidably mounted in bed 10, and having a piston 31 mounted thereon which is reciprocable in cylinder 32. Feed screw 30 is connected to wheel support 11 through vertical shaft 35 having a worm wheel 36 at the lower end in operative engagement with the threads of feed screw 30. The upper end of shaft 35 has a worm wheel 40 connected through suitable gearing to feed hand wheel 45. Hand wheel 45 may be actuated manually or by power to rotate shaft 35 and move wheel support 11 relative to feed screw 30 and bed 10.

Power means for rotating hand wheel 45 consists of piston 50 in cylinder 51. Piston 50 is connected through piston rod 52 which has rack teeth 53 in engagement with pinion 54 which, in turn, engages pinion 55 on hand wheel 45. Adjusting screw 60 provides for fine adjustment of hand wheel 45 and the associated feed mechanism.

Means is provided for stopping or preventing the advance movement of wheel support 11. The means consists of a cylinder 70 in wheel support 11, piston 71 in cylinder 70, and a positive stop 72 on bed 10 in the path of piston 71. The end of cylinder 70 opposite the positive stop 72, is connected to a hydraulic system arranged to supply fluid under pressure to cylinder 70 to stop or prevent the advance movement of wheel support 11, to retract wheel support 11 or to advance said wheel support 11 at a controlled rate.

The feed mechanism may also be adjusted by turning feed screw 30. The means for turning feed screw 30 consists of a worm gear 105 attached to feed screw 30 and in operative engagement with worm 106 at one end of shaft 107. At the other end of shaft 107 is a worm gear 108 in operative engagement with worm 109 rotatably supported in housing 110. Worm 109 is mounted on shaft 115 having a ratchet wheel 116, a feed advance pawl 117 and a feed retract pawl 118. Pawl 117 is actuated by fluid motor 120. Pawl 118 is actuated by fluid motor 121.

Operation

Grinding wheel support 11 is advanced for a grinding operation by introducing fluid under pressure to the right hand end of cylinder 32, shifting feed screw 30, vertical shaft 35 and wheel support 11 to the left until feed screw 30 reaches the end of its movement.

Fluid is then directed to the right hand end of cylinder 51, shifting piston 50 and piston rod 52 to the left to rotate hand wheel 45 and associated feed mechanism including shaft 35 to further advance wheel support 11 after grinding wheel 12 has engaged the work. In order to move wheel support 11 by piston 50, a strain is introduced into the feed mechanism.

When the grinding operation has proceeded to the point where cam 80 engages the feed completion limit switch 81 and piston 71 engages positive stop 72, solenoid 82 is energized, shifting valve 83 to the right and directing fluid under pressure from line 84 at a pressure determined by relief valve 85 through line 86 to valve 90. Valve 90 is held in left hand position by spring 91 and directs fluid under pressure from line 86 to cylinder 70 at the pressure of relief valve 85 to prevent further movement of wheel support 11. By thus stopping wheel

support 11, additional strain is introduced into the feed mechanism.

The grinding operation proceeds without feed and performs a sparkout or round-out operation in the case of plunge grind in a center-type machine in response to relief of strain in the workpiece.

In a centerless machine, arranged with through feed grinding, the wheel in this position is set for grinding a series of workpieces to a predetermined size.

When a post process gauge (not shown) shows that workpieces are not being ground to size, the operator shifts valve 100 to the right, connecting cylinder 70 with exhaust for a brief period and allowing wheel support 11 to advance in response to the strain in the feed mechanism by an amount sufficient to cause workpieces to be ground to a predetermined size.

The amount of oversize is indicated by the post process gauge (not shown) and wheel support 11 may advance a corresponding amount, as shown by indicator 130 suitably positioned to show the movement of wheel support 11.

If, due to unusual circumstances, the post process gauge (not shown) shows that the work is being ground undersize, the operator may shift valve 90 to the right against spring 91 and connect cylinder 70 with higher pressure determined by the setting of relief valve 92. In response to this pressure, cylinder 70 and wheel support 11 will move to the right until indicator 130 shows that wheel support 11 has been retracted by the amount of undersize shown by the post process gauge (not shown).

If, after wheel support 11 has been advanced, the advance has not been sufficient to correct the error shown by the post process gauge (not shown), additional strain can be introduced into the feed mechanism by further rotation of hand wheel 45 either direct or through adjusting screw 60, or by rotation of feed screw 30 by ratchet wheel 116 and either of pawls 117 or 118. During this adjusting operation, valves 90 and 100 are in the normal position shown and valve solenoid 82 is energized so that low pressure fluid is applied to piston 71 to prevent further advance of wheel support 11 until the addition of strain in the feed mechanism is completed. Valve 100 is again shifted momentarily to the right to connect cylinder 70 briefly with exhaust to permit further advance of wheel support 11 in response to relief of the strain in the feed mechanism.

We claim:

1. In a feed control mechanism for a machine tool having a bed, a tool support slidably mounted on said bed, a work support, a cutting tool mounted on said tool support, feeding means for advancing and retracting said tool support relative to said work support including a feed screw, a piston and cylinder attached to said tool support, a positive stop in the path of said piston, a supply of fluid under pressure connected to said cylinder, means to advance said feeding means while said tool support is held against movement by said positive stop and the pressure in said cylinder, and means to connect said cylinder with a lower pressure.

2. In a feed control mechanism for a machine tool having a bed, a tool support slidably mounted on said bed, a work support, a cutting tool mounted on said tool support, feeding means for advancing and retracting said tool support relative to said work support including a feed screw, a piston and cylinder attached to said tool support, a positive stop in the path of said piston, a supply of fluid under pressure connected to said cylinder, means to advance said feeding means while said tool support is held against movement by said positive stop and the pressure in said cylinder, means to connect said cylinder with a lower pressure, and an indicator in the path of said tool support to show movement of said tool support while said cylinder is connected to said lower pressure.

3. A grinding machine comprising a bed, a grinding wheel support slidably mounted on said bed, a work

support, a grinding wheel rotatably mounted on said wheel support, feeding means for advancing and retracting said wheel support relative to a workpiece, means to stop the movement of said wheel support comprising a piston and cylinder attached to said wheel support, means to maintain pressure in said cylinder sufficient to stop or prevent movement of said wheel support, and means to change the pressure in said cylinder to effect adjustment of said wheel support in either direction.

4. A grinding machine comprising a bed, a grinding wheel support slidably mounted on said bed, a work support, a grinding wheel rotatably mounted on said wheel support, feeding means for advancing and retracting said wheel support relative to a workpiece, means to stop the movement of said wheel support comprising a piston and cylinder attached to said wheel support, means to maintain pressure in said cylinder sufficient to stop or prevent movement of said wheel support, means to change the pressure in said cylinder to effect adjustment of said wheel support in either direction, and an indicator on said bed in the path of said wheel support to show the amount of said adjustment.

5. A grinding machine comprising a bed, a grinding wheel support slidably mounted on said bed, a work support, a grinding wheel rotatably mounted on said wheel support, feeding means for advancing and retracting said wheel support relative to a workpiece, means to stop the movement of said wheel support comprising a piston and cylinder attached to said wheel support, means to maintain pressure in said cylinder sufficient to stop or prevent movement of said wheel support, means to change the pressure in said cylinder to effect adjustment of said wheel support in either direction, and an indicator on said bed in the path of said wheel support to show the amount of said adjustment.

6. In a feed control mechanism for a machine tool

having a bed, a tool support slidably mounted on said bed, a work support, a cutting tool mounted on said tool support, feeding means for advancing and retracting said tool support relative to said work support including a feed screw, a piston and cylinder attached to said tool support, a positive stop in the path of said piston, a supply of fluid under pressure connected to said cylinder, means to advance said feeding means while said tool support is held against movement by said positive stop and the pressure in said cylinder, a valve in said fluid supply normally in position to connect said cylinder with exhaust, means actuated by said feeding means to shift said valve to connect said cylinder with pressure to stop said wheel support, means to connect said cylinder with a lower pressure, and an indicator in the path of said tool support and graduated to show movement of said tool support while said cylinder is connected to said lower pressure.

7. A grinding machine having a bed, a grinding wheel support slidably mounted on said bed, a work support, a grinding wheel rotatably mounted on said wheel support, manually operable feeding means for advancing and retracting said wheel support relative to a workpiece, a piston and cylinder attached to said wheel support, a positive stop in the path of said piston, a supply of fluid under pressure high enough to prevent movement of said piston in said cylinder, means to advance said feeding means an amount in excess of the desired movement of said wheel support while said piston prevents movement of said wheel support, an indicator in the path of said wheel support, means to prevent movement of said wheel support or to adjust said wheel support

in either direction until said indicator shows the desired movement comprising means to control the pressure in said cylinder.

8. A grinding machine having a bed, a grinding wheel support slidably mounted on said bed, a work support, a grinding wheel rotatably mounted on said wheel support, manually operable feeding means for advancing and retracting said wheel support relative to a workpiece, a piston and cylinder attached to said wheel support, a positive stop in the path of said piston, a supply of fluid under pressure high enough to prevent movement of said piston in said cylinder, means to advance said feeding means an amount in excess of the desired movement of said wheel support while said piston prevents movement of said wheel support, an indicator in the path of said wheel support, a valve operable in one position to permit exhaust of fluid from said cylinder and in the other position to prevent exhaust of fluid from said cylinder, and a second valve operable in one position to supply fluid under pressure to said cylinder high enough to stop movement of said wheel support and in the other position to supply fluid under a higher pressure to retract said wheel support.

9. A grinding machine having a bed, a grinding wheel support slidably mounted on said bed, a work support, a grinding wheel rotatably mounted on said wheel support, manually operable feeding means for advancing and retracting said wheel support relative to a workpiece, a piston and cylinder attached to said wheel support, a positive stop in the path of said piston, a supply of fluid under pressure high enough to prevent movement of said piston in said cylinder, means to advance said feeding means an amount in excess of the desired movement of said wheel support while said piston prevents movement of said wheel support, an indicator in the path of said wheel support, means to prevent movement of said wheel support or to adjust said wheel support in either direction until said indicator shows the desired movement, and means to advance said wheel support comprising means to reduce the pressure in said cylinder until said indicator shows the desired movement.

10. In a feed control mechanism for a machine tool having a bed, a tool support slidably mounted on said bed, a work support, a cutting tool mounted on said tool support, feeding means for advancing and retracting said tool support relative to said work support, a piston and cylinder attached to said tool support, a positive stop in the path of said piston, a supply of fluid under pressure connected to said cylinder, an indicator in the path of said tool support and graduated to show movement of said tool support, means to effect adjustments of said feeding means and said tool support while said piston is held against said positive stop, said adjustments being in a direction to correct any variations in size of a workpiece, the amount of said adjustments being at least the amount of said variations, and a valve operable to change the pressure in said cylinder to permit said feeding means to move said tool support until said indicator shows that the correction has been completed.

11. In a feed control mechanism for a machine tool having a bed, a tool support slidably mounted on said bed, a work support, a cutting tool mounted on said tool support, feeding means for advancing and retracting said tool support relative to said work support, a piston and cylinder attached to said tool support, a positive stop in the path of said piston, a supply of fluid under pressure connected to said cylinder, an indicator in the path of said tool support and graduated to show movement

of said tool support, means to effect adjustments of said feeding means and said tool support while said piston is held against said positive stop, said adjustments being in a direction to correct any variations in size of a workpiece, the amount of said adjustments being at least the amount of said variations, a valve operable to connect said cylinder alternately with pressure and exhaust, and a second valve operable to connect said pressure connection alternately with high and low pressure fluid supplies.

10 12. In a feed control mechanism for a machine tool having a bed, a tool support slidably mounted on said bed, a work support, a cutting tool mounted on said tool support, feeding means for advancing and retracting said tool support relative to said work support, a piston and cylinder adapted to be moved relative to one another by movement of said tool support, a positive stop in the path of said piston, a supply of fluid under pressure connected to said cylinder, means to actuate said feeding means while said tool support is held against movement by the pressure in said cylinder, and means to connect said cylinder with a lower pressure.

15 13. A grinding machine having a bed, a grinding wheel support slidably mounted on said bed, a work support, a grinding wheel rotatably mounted on said wheel support, manually operable feeding means for advancing and retracting said wheel support relative to a workpiece, a piston and cylinder attached to said wheel support, a positive stop in the path of said piston, a supply of fluid under pressure high enough to prevent movement of said piston in said cylinder, means to advance said feeding means an amount in excess of the desired movement of said wheel support while said piston prevents movement of said wheel support, a valve operable in one position to permit exhaust of fluid from said cylinder and in the other position to prevent exhaust of fluid from said cylinder, and a second valve operable in one position to supply fluid under pressure to said cylinder high enough to stop movement of said wheel support and in the other position to supply fluid under a higher pressure to retract said wheel support.

20 14. In a feed control mechanism for a machine tool having a bed, a tool support slidably mounted on said bed, a work support, a cutting tool mounted on said tool support, feeding means for advancing and retracting said tool support relative to said work support, a piston and cylinder attached to said tool support, a positive stop in the path of said piston, a supply of fluid under pressure connected to said cylinder, means to effect adjustments of said feeding means and said tool support while said piston is held against said positive stop, said adjustments being in a direction to correct any variations in size of a workpiece, the amount of said adjustments being at least the amount of said variations, a valve operable to connect said cylinder alternately with pressure and exhaust, and a second valve operable to connect said pressure connection alternately with high and low pressure fluid supplies.
